UNITED STATES PATENT OFFICE.

DONALD RAWSTRON, OF HARVEY, AND HENRY RAWSTRON, OF CHICAGO,
ILLINOIS, ASSIGNORS TO JAMES FRANCIS HILL, OF CHICAGO, ILLINOIS.

BRAKE-SHOE.

SPECIFICATION forming part of Letters Patent No. 717,620, dated January 6, 1903.

Application filed March 31, 1902. Serial No. 100,792. (No model.)

To all whom it may concern:

Be it known that we, DONALD RAWSTRON, of the town of Harvey, and HENRY RAWSTRON, of 7127 Wentworth avenue, in the city 5 of Chicago, State of Illinois, have invented certain new and useful Improvements in Brake-Shoes, of which the following is a specification.

Our brake-shoe is made of any standard 10 shape in cross-section and is preferably made of soft cast iron or steel, in which are molded hard-metal inserts of special design, as hereinafter described, for the double purpose of dressing the wheel tread and flange and preventing 15 the too rapid wear of the brake-shoe, a pocket or pockets being also formed in the shoe filled with a friction-creating material for the purpose of furnishing the necessary friction with but little wear on the wheel-tire. 20 It is well known to those acquainted with the art that the rolling motion of a wheel upon a rail causes a groove to be worn upon the tread of the wheel adjacent to the flange and that the wheel-flange as the wheel-tread 25 becomes worn is left projecting.

It is one of the objects of our invention to so construct a brake-shoe that it will wear the wheel-tread to the greatest extent where the wheel-tread is least worn by the rail and 30 so that it will dress down the edge of the flange and tend to maintain it in proper proportion to the tread of the wheel. We attain this object by molding in the shoe hard-metal inserts, preferably formed of the hardest 35 white cast-iron obtainable. These inserts may be of any desired shape, though a substantially triangular form is that which we deem preferable. These hard-metal inserts are molded in the face of the shoe with their 40 bases adjacent to the outer surface of the shoe, their points or apexes being turned inward and approaching to the flange-groove. Thus these hard-metal inserts present inclined shearing edges across the face of the 45 shoe. As well as presenting shearing edges, the operative sides of the triangular inserts are set back at an acute angle to the wearing-surface, so that a very efficient tool edge is formed by the hard metal of the inserts at 50 their points of junction with the soft metal of the shoe. Owing to the triangular shape

and described position of the hard-metal inserts it follows that the greatest wearing-surface of hard metal is in contact with the least-worn portion of the wheel, and at this 55 point, therefore, the wearing action of the brake-shoe will be the greatest, resulting in the truing down of the tread of the wheel. At the same time, as the brake-shoe possesses a comparatively large area of hard metal, its 60 braking or frictional power is necessarily considerably decreased. We compensate for this by forming in the face of the shoe pockets of substantially the same shape (in plan view) as the hard-metal inserts, but oppositely 65 set—that is, with their bases adjacent to the flange-groove and their apexes toward the outer side of the shoe. The walls of these pockets are inclined to give a dovetail section to the pockets, so that they will effectively 70 retain the filler, which we will now describe. While any filler may be used in these pockets which will increase the frictional action of the shoe and which will preferably absorb ground-off particles of metal, we prefer to use 75 the composition set out in United States Patent No. 596,132. This patent describes and claims a composition consisting of comminuted iron, asphaltum, and Wahsatch rock, intermixed in substantially the proportion of 80 eighteen parts of iron, one part of asphaltum, and one part of Wahsatch rock, by weight. The composition will be prepared and the pockets filled substantially in the manner set forth in that patent. Owing to the arrangement described the greatest surface of this 85 frictional compound is applied to the most-worn part of the wheel, fully compensating for the loss of braking power due to the hard-metal inserts, while producing very little wear 90 on this rail-worn portion of the wheel-tread. This composition absorbs the ground-off particles from the wheel and brake-shoe and by retaining them adds greatly to the life of the shoe. The flange-groove of the shoe is also 95 provided with hard-metal inserts and pockets of filler, the inserts having, preferably, pointed operative ends.

In Figure 1 we show a plan view of the face of a shoe adapted for flanged wheels. In Fig. 100 2 we show a similar view of the shoe adapted for wheels without flanges. In Fig. 3 we show a

cross-section through the line $x'y$ in Fig. 1; in Fig. 4, a cross-section through the line $y'z$ in Fig. 1. In Fig. 5 we show a diagrammatical longitudinal section of a shoe with a single 5 insert applied to a wheel, and in Fig. 6 we show in elevation and plan several forms of inserts.

In Fig. 1, A are the hard-metal inserts in the face of the shoe, and B the hard-metal inserts in the flange-groove. The inserts are substantially triangular, as described, to form the shearing edges C, one being operative when the wheel is revolving in one direction and the other when the wheel is moving in 15 the opposite direction. The operative sides a are inclined at an acute angle to the wearing-surfaces to give the edge of the insert the effective tool action desired. In order to retain the inserts in position, we form the lips 20 or flanges b on each insert, so that when the soft cast-iron of the shoe is cast around them it will securely hold the inserts in position. In the flange-groove the inserts will be similarly held in position. They will not, however, 25 usually be of triangular shape, but may be formed of any suitable shape, preferably having their operative sides of a suitable shearing shape. Their operative sides will also generally be set at an acute angle to 30 their wearing-surfaces, similar to the sides of the larger inserts in the face of the shoe. A small insert D is preferably molded in the face of the brake-shoe at the end opposite to the hole E, through which passes the bolt used 35 when securing the shoe to the brake-head. The operative sides of the insert D are shown curved, giving them a shearing action, though a diamond or other shape might also be used. The operative sides of this insert may also 40 be set at an acute angle to the wearing-surface, as is the case with the inserts A and B. The pockets of filler in the face of the shoe and in the flange-groove are lettered F and G, respectively, and are shaped as already described. 45

In a shoe, such as shown in Fig. 2, intended for flangeless wheels the inserts are so arranged and shaped that the greatest wearing or cutting action is secured at each side of 50 the brake-shoe, as the center of the brake-shoe is the portion which comes in contact with the most-worn part of the wheel-tread. The arrangement of the pockets of frictional compound is of course just opposite to that 55 of the metal inserts, so that in this form of shoe the arrangement is substantially the same as in Fig. 1, with the greatest surface of hard metal opposed to the least-worn parts of the tread of the wheel and the greatest surface of frictional compound in contact with 60 the most-worn portions of the wheel-tread.

Several important features relating to our invention should be noted. In the first place, the body of the brake-shoe must be of 65 the soft cast iron or steel of such a quality that it will not chill or only chill to a very small extent when cast around the hard-

metal inserts. This insures the formation of clearly-defined cutting edges at the operative sides of the inserts. If a quality of iron were used for the body of the shoe such as would readily chill and harden, our purpose in using the inserts would be largely frustrated. In the second place, it is difficult to form an effective cutting edge if the operative sides 75 of the inserts are at right angles to or form obtuse angles with the wearing-surfaces. As illustrated in Fig. 6, a dressing-tool should form a real cutting edge. Inserts as they have hitherto been used have formed merely 80 glancing edges. It is also important to secure the best effect that the operative sides of the inserts should be set at a shearing angle across the face of the shoe, as they thus act most effectively and at the same time are 85 not apt to gouge into soft spots on the rim of a wheel. The third important feature is the arrangement of pockets containing a frictional filler in such a manner as to compensate for the loss of braking power due to the 90 use of the hard-metal inserts. The fourth feature consists in the arrangement of the inserts and the pockets of filler so that the dressing action of the shoe is greatest on the less-worn parts of the wheel and the frictional effect greatest on the most-worn parts 95 of the wheel. In this connection the arrangement of the inserts and pockets so that a dressing effect is produced on the flange edge, which ordinarily is not worn at all, 100 adds considerably to the value of the shoe. Another point to be noted is the effect on the shoe of the use of an absorptive filler in the pockets. It is well known that the accumulation of the ground-off particles (resulting 105 from the application of the shoe to the wheel) on any portion of the face of the brake-shoe and the final fusing of them together by the generated heat produces an uneven surface on the shoe-face, thereby wearing irregular 110 channels and tearing the wheel tread and flange and finally putting the wheel out of action. An absorptive filler takes up these particles, using up this otherwise waste material in creating friction, thus increasing 115 the life of the shoe. The life of the wheel is also prolonged, owing to the wheel-face being kept free from the roughness just described. Another advantage resulting from the use of this filler is that it prevents the 120 hard portions of the surface of the brake-shoe from glazing, thus establishing a superior frictional contact-surface and developing a greater degree of friction in consequence. 125

Although we prefer to use an absorptive filler such as described, yet other friction-creating fillings might be employed with a considerable degree of advantage. Also for some purposes the hard sections instead of being formed by inserts might be formed by using a chilling-iron and casting the shoe with hard chilled sections. Though the dressing 130 effect of such a shoe would be reduced,

yet the advantages of prolonged life without loss of braking power would still be retained.

What we claim as our invention is—

1. A cast-metal brake-shoe having a hard-metal insert molded in its face, said insert being so shaped that the metal of the body of the shoe retains it in place, and also having an operative side formed at an acute angle to its wearing-surface so as to present an efficient cutting edge to act on a wheel, substantially as described. 5
2. A cast-metal brake-shoe having a hard-metal insert molded in its face, said insert being so shaped that the metal of the body of the shoe retains it in place, and having an operative side set diagonally across the shoe and also formed at an acute angle to its wearing-surface so as to present an efficient cutting edge to act on a wheel, substantially as 15 described. 20
3. A cast-metal brake-shoe having a substantially triangular faced hard-metal insert molded in its face with its base at or near the outer side of the shoe, the said insert having lugs or projections formed thereon to retain it in place and also having an operative side formed at an acute angle to its wearing-surface so as to present an efficient cutting edge to act on a wheel, substantially as described. 25 30
4. A cast-metal brake-shoe having a substantially triangular faced hard-metal insert molded in its face with its base at or near the outer side of the shoe, the said insert having lugs or projections formed thereon to retain it in place and also having its operative sides formed at an acute angle to its wearing-surface so as to present an efficient cutting edge to act on a wheel, substantially as described. 35 40
5. A cast-metal brake-shoe having hard sections formed therein in the process of molding, and provided with pockets filled with a frictional absorptive compound whereby the loss of braking power due to the hard-metal sections is compensated for by the pockets of frictional compound and ground-off particles of metal from the shoe and wheel are absorbed, substantially as described. 45 50
6. A cast-metal brake-shoe having hard sections formed therein in the process of molding, and provided with pockets filled with a frictional filler, the hard sections and pockets being so arranged and proportioned that the greatest surface of hard metal is located at that part of the shoe which contacts with the least-worn part of a wheel and the greatest surface of frictional filler at that part of the shoe in contact with the most-worn part of a wheel, substantially as described. 55 60
7. A cast-metal brake-shoe having hard-metal inserts secured therein in the process of molding forming transverse cutting edges on the shoe at their lines of contact with the softer metal, and provided with pockets filled 65 70
8. A cast-metal brake-shoe having a substantially triangular faced hard section formed therein with its base at or near the outer side and provided with a similarly-shaped but oppositely-set pocket filled with a frictional filler, substantially as described. 75 7c
9. A cast-metal brake-shoe having a substantially triangular faced hard-metal insert secured therein in the process of molding, with its broad portion at or near the outer side and provided with a similar triangular-faced but oppositely-set pocket filled with a frictional filler, substantially as described. 80 85
10. A cast-metal brake-shoe having a substantially triangular faced hard-metal insert molded in its face with its base at or near the outer side of the shoe, the said insert having lugs or projections formed thereon to retain it in place, and also having its operative side formed at an acute angle to its wearing-surface so as to present an efficient cutting edge to act on a wheel, in combination with a substantially triangular faced pocket of frictional filler set oppositely to the insert, substantially as described. 85 90
11. A cast-metal brake-shoe having a plurality of substantially triangular faced hard-metal inserts secured therein in the process of molding, and provided with a plurality of alternated triangular-faced pockets filled with a frictional filler, the inserts being set with their bases adjacent to the outer side of the shoe and the pockets of filler with their bases adjacent to the inner side of the shoe, substantially as described. 95 100
12. A cast-metal brake-shoe shaped to fit a flanged wheel having hard-metal inserts secured therein in the process of molding both in the bottom of the flange-groove and in the face of the shoe, the inserts in the face of the shoe being so shaped and arranged as to give a larger proportion of hard metal at that part of the shoe which contacts with the least-worn part of a wheel, in combination with pockets of frictional filler located both in the bottom of the flange-groove and in the face of the shoe, the pockets of filler in the face being so shaped and arranged as to give the greatest surface of frictional filler at that part of the shoe which contacts with the least-worn part of the tread of a wheel, substantially as described. 105 110 115
